UNITED STATES PATENT OFFICE

DON W. BISSELL AND FREDERICK H. KRANZ, OF BUFFALO, NEW YORK, ASSIGNEES TO NATIONAL ANILINE & CHEMICAL COMPANY, INC., OF NEW YORK, N. Y., A CORPORATION OF NEW YORK

CHLORINATION OF 3-HYDROXYBENZALDEHYDE

No Drawing.

Application filed November 22, 1921. Serial No. 517,076.

This invention relates to improvements in the chlorination of 3-hydroxybenzaldehyde, and more particularly to improvements in the production of 2,6-dichlor-3-hydroxybenzaldehyde. The invention also includes, as a new product, a mono-chlor derivative of 3-hydroxybenzaldehyde, namely, 2-chlor-3-hydroxybenzaldehyde. The invention also includes improvements in the control of the chlorination process whereby the desired chlorination products may be obtained in substantially maximum yields.

The present invention is based upon the discovery that the chlorination of 3-hydroxybenzaldehyde can be carried out in stages, and with production of substantially maximum yields of the monochlor-, dichlor-, or trichlor- derivatives of 3-hydroxybenzaldehyde by passing chlorine into a warm glacial acetic acid solution of 3-hydroxybenzaldehyde. The invention also includes an improved method of controlling the process, whereby chlorination products of the desired degree of chlorination can be obtained in substantially the maximum yield and with a minimum production of admixed higher and lower chlorination products.

It is known that 3-hydroxybenzaldehyde can be chlorinated by the action of chlorine upon a warm solution of 3-hydroxybenzaldehyde in glacial acetic acid, but so far as we are aware, di-chlor- and trichlor-3-hydroxybenzaldehyde are the only products that have been obtained in this way. According to the present invention, however, the lower as well as the higher chlorination products, and especially dichlor-3-hydroxybenzaldehyde, can be produced with substantially maximum yields.

We have found that chlorination of 3-hydroxybenzaldehyde in warm glacial acetic acid solution can be so regulated and controlled that a product consisting essentially of monochlor-3-hydroxybenzaldehyde can be produced with a minimum production of higher chlorination products; and that the dichlor-3-hydroxybenzaldehyde can similarly be produced as the principal product of the process; while, by further continuing the process, and by proper regulation of the proc-

ess, the trichlor-3-hydroxybenzaldehyde can also be produced as the principal product with a minimum production of by-products such, for example, as aldehyde-trichlor-quinone-dichloride, etc.

We have found that, when the chlorination of 3-hydroxybenzaldehyde is so regulated that monochlor-3-hydroxybenzaldehyde is the principal chlorination product, the monochlor-3-hydroxybenzaldehyde which is formed consists principally of a mixture of 2-chlor-3-hydroxybenzaldehyde and 6-chlor-3-hydroxybenzaldehyde. The 2-chlor-3-hydroxybenzaldehyde, when purified, has a melting point of about 139°-139.5° C., and the 6-chlor-3-hydroxybenzaldehyde, when purified, has a melting point of about 110.5°-111.5° C. The former of these two substances in so far as we are aware, has not been heretofore produced, and we accordingly regard it as new. The mixture of the two compounds has pronounced sternutatory properties. It may serve as an intermediate in the preparation of other chemical compounds as dye stuffs.

The dichlor-3-hydroxybenzaldehyde which is produced consists chiefly of 2,6-dichlor-3-hydroxybenzaldehyde, and, when purified, melts at about 142°-142.2° C.; the trichlor-3-hydroxybenzaldehyde which is formed is the 2,4,6-trichlor-3-hydroxybenzaldehyde, and, when purified, melts at about 115.5°-116.5° C.

We have discovered that, in the chlorination of 3-hydroxybenzaldehyde in glacial acetic acid solution by the action of chlorine, the relative stage or degree of chlorination may be approximately determined by noting the temperature at which the solution is just saturated with respect to the product or products which may be present or are formed during the course of the reaction. This temperature is denoted as the saturation temperature. Within limits, for each definite concentration of the components which comprise the solution there is a temperature at which complete solution just takes place. For example, one mol of 3-hydroxybenzaldehyde dissolved in approximately three and six-tenths mols of glacial acetic acid produces a saturated solution at a temperature of about 100

53° C. Upon passing chlorine into this solution, and as chlorination progresses, the temperature of saturation first falls to a minimum and then rises to a definite maximum, about 62° C., at which temperature a mixture of the monochlor-3-hydroxybenzaldehydes is present in maximum quantity. Upon continued chlorination, the saturation temperature again falls and then rises to another definite maximum, about 93° C., at which temperature dichlor-3-hydroxybenzaldehyde is present in greatest quantity. Upon further chlorination the temperature of saturation again falls to a minimum and again rises to a maximum, about 65° C., at which temperature the trichlor-3-hydroxybenzaldehyde is the main product present in the solution. The temperatures of 62° C., 93° C., and 65° C., as illustrated above are designated as maximum saturation temperatures.

The invention will be further illustrated by the following specific examples, the parts being by weight:

25 Example 1.—240 parts of 3-hydroxybenzaldehyde are dissolved in 430 parts of glacial acetic acid, and chlorine is passed into the agitated solution, which is maintained at a temperature of 65°-70° C., until crystals 30 begin to separate. The temperature of the solution is then raised and maintained at 75°-80° C., and the chlorination continued until enough chlorine has been taken up by the solution to correspond to the formation 35 and maximum yield of dichlor-hydroxybenzaldehyde. This stage of chlorination is determined by removing a sample of the mixture, cooling the same with vigorous agitation until crystals separate, and then carefully warming with observation of the temperature until all of the crystals just disappear. When chlorination has proceeded to such an extent that a test sample shows 93° C. as the temperature of disappearance of 40 crystals, the chlorination is discontinued. The chlorinated mixture is then poured into about three times its volume of cold water, and the crystals which separate are filtered off and washed with water. The crude dichlor-hydroxybenzaldehyde thus obtained 45 melts at about 125°-135° C. and may, if desired, be purified by recrystallization from acetic acid.

50 Example 2.—240 parts of 3-hydroxybenzaldehyde are dissolved in 860 parts of glacial acetic acid, and chlorine is passed into the agitated solution, which is maintained at a temperature of about 50° C., until crystals 55 begin to separate out. The temperature of the solution is then raised and maintained at about 60°-70° C., and the chlorination continued until a sample, cooled until crystals appear, will again become clear upon raising the temperature to 78° C. The chlorinated mixture is then poured into about

60 three times its volume of cold water, and the precipitate filtered off and washed. The crude dichlor-hydroxybenzaldehyde thus obtained melts at about 130°-135° C., and may be purified, if desired, by recrystallization 65 from acetic acid.

70 It will be noted that in the progressive chlorination of an acetic acid solution of 75 3-hydroxybenzaldehyde there are successively produced three maximum saturation temperatures, each representing in order of production the point at which monochlor-, dichlor- and trichlorhydroxybenzaldehyde, respectively, is present in the largest amount. With other and different concentrations of 80 the components comprising the acetic acid solution, the individual maximum saturation temperatures will vary, but in any case the point where the greatest amount of any one of the components is present will be 85 that at which the maximum saturation temperature is shown in its proper sequence. A careful preliminary pre-determination of 90 the various maximum saturation temperatures for any given concentration will enable thereafter the chlorination of such concentrations to be carried out and controlled by means of such pre-determined maximum temperatures, and in this way one may obtain the maximum yields of either monochlor-, dichlor- or trichlorhydroxybenzaldehyde as may be desired. Of the three maximum saturation temperatures, the highest is 95 that produced when di-chlorhydroxybenzaldehyde is present in greatest quantity.

100 It will thus be seen that the present invention makes possible the regulated chlorination of 3-hydroxybenzaldehyde and the production, as the principal products of the chlorination, of either the monochlor-3-hydroxybenzaldehydes, or the 2,6-dichlor-3-hydroxybenzaldehyde, or the trichlor-3-hydroxybenzaldehyde. In particular, the present invention makes possible the production 105 of the 2,6-dichlor-3-hydroxybenzaldehyde or of the 2 monochlor-3-hydroxybenzaldehydes, as the main products of the process. It will also be seen that the present invention provides a new and improved method of 110 controlling the chlorination whereby the desired products can be produced with a minimum production of other chlorination products.

115 We claim:

120 1. In the production of a halogenated derivative of 3-hydroxybenzaldehyde by subjecting 3-hydroxybenzaldehyde in acetic acid solution to the action of a halogen, the improvement which comprises determining the 125 saturation temperature of the reaction mixture from time to time and continuing the addition of the halogen until the saturation temperature of the reaction mixture rises to a maximum.

130 2. The method of producing a monohalo-

generated derivative of 3-hydroxybenzaldehyde which comprises introducing a halogen into an acetic acid solution of 3-hydroxybenzaldehyde with heating, closely observing the saturation temperature throughout the reaction and continuing the addition of the halogen only until the saturation temperature of the reaction mixture has reached substantially a maximum corresponding to the maximum yield of monohalogenated derivative.

3. In the production of a chlorinated derivative of 3-hydroxybenzaldehyde by subjecting 3-hydroxybenzaldehyde in acetic acid solution to the action of chlorine, the improvement which comprises intermittently determining the saturation temperature of the reaction mixture and continuing the addition of chlorine until the saturation temperature of the reaction mixture has reached the maximum value associated with the chlorinated derivative of 3-hydroxybenzaldehyde.

4. In the production of chlorine derivatives of 3-hydroxybenzaldehyde by subjecting 3-hydroxybenzaldehyde in acetic acid to the action of chlorine, the improvement which comprises observing the changes in at least one physical property of the reaction mixture throughout the chlorination and terminating the chlorination at approximately the point at which the acetic acid solution becomes just saturated at a predetermined temperature with respect to a chlorine derivative.

5. In the production of chlorine derivatives of 3-hydroxybenzaldehyde by subjecting 3-hydroxybenzaldehyde in acetic acid solution to the action of chlorine, the improvement which comprises controlling the degree of chlorination by withdrawing from time to time test portions of the reaction mixture, cooling said test portions until the formation of crystals occurs, and determining the temperature at which the separated crystals disappear into solution upon warming said test portion and terminating the chlorination when a predetermined saturation temperature is reached.

6. In the production of the chlorinated derivatives of 3-hydroxybenzaldehyde by subjecting 3-hydroxybenzaldehyde in acetic acid solution to the action of chlorine the improvement which comprises intermittently withdrawing test samples of the reaction mixture and continuing the chlorination until the temperature at which the separated crystals of a test sample disappear on heating reaches substantially a maximum point.

7. The process of producing a monochlor derivative of 3-hydroxybenzaldehyde which comprises heating an acetic acid solution of 3-hydroxybenzaldehyde and passing chlorine into the solution until an amount of chlorine has been taken up corresponding to a maximum yield of a monochlor derivative.

8. The method of producing monochlor derivatives of 3-hydroxybenzaldehyde which comprises heating an acetic acid solution of 3-hydroxybenzaldehyde, subjecting the solution to the action of chlorine, determining the saturation temperature of the reaction mixture from time to time and discontinuing the chlorination at substantially that point at which the acetic acid solution becomes just saturated at a predetermined temperature with respect to the monochlor derivative.

9. As a new product, 2-chlor-3-hydroxybenzaldehyde having a melting point of about 139° to 139.5° C.

10. As a new product, a mixture of monochlorinated derivatives of 3-hydroxybenzaldehyde containing 2-chlor-3-hydroxybenzaldehyde and 6-chlor-3-hydroxybenzaldehyde.

11. In the production of a chlorinated derivative of 3-hydroxybenzaldehyde by subjecting a solution of the 3-hydroxybenzaldehyde to the action of chlorine, the improvement which comprises intermittently determining the saturation temperature of the reaction mixture and terminating the chlorination when the saturation temperature approximates the maximum value associated with the chlorine derivative of 3-hydroxybenzaldehyde.

12. In the production of a halogenated derivative of 3-hydroxybenzaldehyde by subjecting 3-hydroxybenzaldehyde in solution to the action of a halogen, the improvement which comprises carefully observing changes in a property of the reaction mixture during the reaction and terminating the halogenation when the saturation temperature approximates the maximum value associated with a particular chlorine derivative of 3-hydroxybenzaldehyde as indicated by the observed changes in a property of the reaction mixture.

13. In the production of a halogenated derivative of 3-hydroxybenzaldehyde by subjecting 3-hydroxybenzaldehyde in acetic acid solution to the action of a halogen, the improvement which comprises maintaining the reaction temperature during the different stages of halogenation at or above the saturation temperature of the reaction mixture.

14. In the production of a halogenated derivative of 3-hydroxybenzaldehyde by subjecting 3-hydroxybenzaldehyde in acetic acid solution to the action of halogen, the improvement which comprises controlling the degree of halogenation by reference to the temperature of saturation of the solution.

15. In the production of a chlorine derivative of 3-hydroxybenzaldehyde by subjecting 3-hydroxybenzaldehyde in acetic acid solution to the action of chlorine, the improvement which comprises controlling the degree of chlorination by reference to the

temperature of saturation of the solution which corresponds to a maximum saturation temperature.

16. The method of producing 2,6-dichlor-3-hydroxybenzaldehyde which comprises treating a solution of 3-hydroxybenzaldehyde in acetic acid, in the ratio of one mol of 3-hydroxybenzaldehyde to approximately three and six tenths mols of acetic acid, with chlorine, intermittently withdrawing test samples of the reaction mixture and continuing the chlorination until the temperature, at which the separated crystals disappear on heating a test sample, reaches substantially 93° C.
17. The method of producing 2,6-dichlor-3-hydroxybenzaldehyde which comprises treating a solution of 3-hydroxybenzaldehyde in acetic acid, in the ratio of one mol of 3-hydroxybenzaldehyde to approximately seven and two tenths mols of acetic acid, with chlorine, intermittently withdrawing test samples of the reaction mixture and continuing the chlorination until the temperature, at which the separated crystals disappear on heating a test sample, reaches substantially 78° C.
18. The method of producing 2,6-dichlor-3-hydroxybenzaldehyde which comprises treating a solution of 3-hydroxybenzaldehyde in acetic acid with chlorine until the temperature at which the separated crystals of a test sample disappear on heating falls to a minimum then rises to a maximum, again falls to a minimum and rises approximately to a second maximum, and then discontinuing the chlorination.
19. The method of producing trichlor-3-hydroxybenzaldehyde, which comprises treating a solution of 3-hydroxybenzaldehyde in acetic acid, in the ratio of one mol of 3-hydroxybenzaldehyde to approximately three and one-half mols of acetic acid, with chlorine, intermittently withdrawing test samples of the reaction mixture and continuing the chlorination until the temperature at which separated crystals disappear on heating a test sample reaches substantially a maximum of about 65° C. after having passed through a higher maximum of about 93° C.
20. As a new product, trichlor-3-hydroxybenzaldehyde.

In testimony whereof we affix our signatures.
